UNITED STATES PATENT OFFICE.

WILLIAM H. McBRIDE, OF ST. LOUIS, MISSOURI.

PAPER-TAPE FOLDER.

1,234,188.

Specification of Letters Patent. Patented July 24, 1917.

Application filed September 4, 1915. Serial No. 49,090.

To all whom it may concern:

Be it known that I, WILLIAM H. McBRIDE, a citizen of the United States, and a resident of the city of St. Louis and State of Missouri, have invented a certain new and useful Improvement in Paper-Tape Folders, of which the following is a specification.

This invention relates to a new system of handling and preserving records in strip form, and more particularly to folding up into book form such long narrow strips of paper as are used in adding machines for recording the items totaled. The invention has for its objects to make up such strips or tape into a form which is convenient for handling and inspection, and which is compact and adapted for filing and for permanent preservation.

Further objects and details of the invention appear in connection with the following description of a suitable folding machine for performing the invention; and what the invention consists in is more particularly defined in the appended claims.

In the accompanying drawings, wherein the same reference characters designate like parts in the several views,

Figure 1 is a front view of a suitable machine for carrying out the invention, showing a tape inserted ready for folding;

Fig. 2 is a plan view of the machine shown in Fig. 1;

Fig. 3 is a vertical cross-section of the same on the line 3—3 in Fig. 4, showing the tape partly looped;

Fig. 4 is a view of the delivery side of the machine, with the tape removed;

Fig. 5 is a vertical cross-section of the machine on the line 5—5 in Fig. 4, showing the tape completely looped and the cover inserted prior to pasting;

Fig. 6 is a view similar to Fig. 5 of the drum and tape, showing the loops folded around the drum ready for pasting; and

Fig. 7 is a perspective view of the completed book.

The folding machine shown in the drawings, comprises a base 10 provided with front and rear pedestals 11 in which is mounted a horizontal axle 12. A drum 13 is journaled for oscillation upon the axle 12. Below the drum is a transversely curved blade 14, which is secured to a cross web 15 connecting the pedestals. The blade 14 is arranged horizontally, and extends nearly from end to end of the drum in proximity

to its under side. The curve of the blade 14 follows the outline of the drum, and the front edge of this blade is sharp and lies close against the surface of the drum for stripping off the loops of tape as they are formed. A vertically movable angle clamp 16 is slidably mounted on the web portion 15 of the frame beneath the curved blade 14. The vertical leg of the angle clamp is arranged below the back edge of the curved blade 14, and the horizontal leg is normally held up against the rear portion of the curved blade tangentially thereto by means of a bell crank lever 17. The curved blade 14 and the horizontal leg of the angle clamp 16 together form a clamping means for holding the loops of tape as they are formed. A finger or latch 18 which is pivoted to the upper arm of the bell crank lever engages under the angle clamp at its middle. The end of the pivoted finger is held in the angle between the vertical and horizontal legs of the angle clamp by means of a small spring.

The bell crank lever is fulcrumed in the base, and its upper arm extends under the drum transversely of its middle and is held up by a spring 19 located in the base. One end of the spring is connected to the lower arm of the bell crank lever and the other end is attached to a nut 20 which can slide in a narrow space in the base. The nut 20 is mounted on an adjusting screw 21, the head of which projects through the side wall of the base where it can be reached with a screw driver. The tension of the spring can be adjusted by means of the screw and nut to suit the paper being folded. The upper end of the bell crank lever has a thumb portion 22 for depressing it to remove the folded tape.

The base or frame has a slot 23 through it on the side of the drum from which the tape or strip of paper is fed for guiding it. The length of this guide slot is adjustable for various widths of paper by means of the guide fingers 24 which are slidable along a graduated rod 25 secured to the base alongside of the slot.

The drum 13 is fitted with a pivoted operating handle 26 for oscillating it back and forth, and this handle is connected by means of the link 27 with the cranked end 28 of the paper clamp rod 29. The opposite ends of the clamp rod 29 are provided with offset or crank portions 30 which are journaled in brackets on the edges of the drum. A paper

folding blade 31 is attached to the drum alongside of the paper clamp rod 29 and parallel to and spaced slightly from the surface of the drum. This folding blade is a 5 tightly stretched thin ribbon of steel, and is graduated like the rod 25 for centering the paper on the drum. The graduations may be marked on the drum instead of on the folding blade if desired.

10 The drum is fitted with a full stroke device comprising a swinging friction detent 32 pivoted on the front pedestal 11 between it and the end of the drum. The lower end of the detent 32 frictionally engages the inner surface of the projecting front edge 15 of the drum barrel, and is held in engagement therewith by one or the other of the two retaining springs 33. The projecting edge of the drum has two depressions or 20 holes 34, which are arranged to engage the detent respectively at the ends of the forward and return strokes of the drum to reverse the detent. A friction spring 35 on the base bears against a raised strip 36 on 25 the edge of the drum at the end of the return stroke or half oscillation of the drum, and this retards the beginning of the looping stroke sufficiently to insure that the handle 26 shall swing around and throw the paper 30 clamp rod 29 into clamping position to feed the paper tape for making the loop. A similar retarding action occurs at the beginning of the return stroke, due to the folding blade 31 being frictionally held by the clamping 35 means for the loop, thereby causing the handle to swing back and raise the paper clamp rod from the drum to permit the paper to run freely beneath it. A stop 37 on the edge of the drum limits the length 40 of the return stroke and thereby determines the length of tape picked up for each loop.

45 The operation of the device is as follows: The tape is led through the guide slot 23 and over the drum passing under the clamp rod 29 and folding blade 31, and five or six inches of its length is pulled through beneath the folding blade, as shown in Fig. 1. The drum is rotated in the direction of movement of the tape by means of the handle until the folding blade brings up against the web 15 and between the curved blade 14 and the angle clamp 16. During this stroke the handle holds the clamp rod 29 tight against the paper, thus causing the paper to 50 be carried around with the drum. The direction of movement of the drum is then reversed, and the folding blade is withdrawn from between the angle clamp and curved blade, leaving the folded end of the loop 55 caught between the two. The paper clamp is automatically raised during the return stroke, and the paper remains motionless, the drum rotating beneath it. At the end of the return stroke the motion of the drum is again reversed, and a second looping stroke 60

65 is made. The direction of movement of the drum can be reversed at either end of the stroke, thereby reversing the position of the detent 32; but the detent 32 prevents reversing the direction of movement of the drum 70 between the ends of the strokes, thus insuring a complete stroke of the drum in each direction.

The forward and back oscillation of the drum is continued until the entire length of 75 tape has been looped up. The loops 38 remain clamped at one end between the angle clamp 15 and curved blade 14, as shown in Figs. 3 and 5. One end of a cover strip 39 is slipped between the last loop formed and 80 the curved blade 14, as shown in Fig. 5. The open ends of the loops are swung up against the drum with one hand, and paste is applied to their overlapping extremities by means of a brush held in the other hand, 85 after which the free end of the tape which was first pulled through the folding blade is brought up and laid over the pasted ends of the loops and against the cover and pasted thereto, as shown in Fig. 6. The free end of 90 the cover is next folded down over the pasted ends of the loops, and the book is complete and may be removed from the clamping blades by pressing down the thumb key 22 on the end of the bell crank lever. The un- 95 pasted extremities of the loops when freed from the clamping blades assume overlapping positions conforming to the overlapping at the pasted ends, thereby making easy 100 turning of the leaves for inspecting their 105 contents.

It is evident that changes in the forms and arrangements of the parts may be made, and the invention is not restricted to the parts and arrangements shown and described. 105

What I claim is:

1. A paper folding device comprising an oscillating drum provided with a paper gripper and folder, in combination with a fixed clamping blade adjacent to said drum 110 and a movable clamping blade coöperating with said fixed blade to receive successively folded loops from said folder and hold them in stacked relationship, and means for releasing said movable clamping blade to release said stacked loops. 115

2. A paper folding device comprising an oscillating drum provided with a paper clamping device, in combination with a fixed clamping blade adjacent to said drum and a 120 movable clamping blade coöperating with said fixed blade to receive successive loops of paper from said drum and hold them in stacked relationship, and means for alternately clamping and releasing said paper 125 clamping device in synchronism with the oscillations of said drum.

3. A paper folding device comprising an oscillating drum provided with a paper gripper and folder, in combination with a 130

fixed clamping blade adjacent to said drum and a movable clamping blade coöperating with said fixed blade to receive successively folded loops from said folder and hold them in stacked relationship, and means for operating said paper gripper to grip the paper on the looping stroke and to release the paper on the return stroke of said drum.

4. A paper folding device comprising a frame, a paper carrier mounted in said frame and movable back and forth in a curved path about a fixed axis, a folder blade mounted flatwise on said paper carrier with its folding edge parallel to said axis for centering the paper, a clamping device arranged in the path of movement of said folder blade to receive the folds of paper from said blade, and a paper guide on said frame arranged parallel to the axis of said paper carrier.

5. A paper folding device comprising a frame, a paper carrier mounted in said frame and movable back and forth in a curved path about a fixed axis, a folder blade mounted flatwise on said paper carrier parallel to its axis for centering the paper, a paper guide on said frame arranged parallel to the axis of said paper carrier, releasable clamping means under the control of the operator on said paper carrier and adjustable means on said paper guide for securing paper of different widths in alignment square with said folder blade, and means for holding the folds of paper in the path of movement of said folding blade.

6. In combination in a paper folding device, a paper looping device comprising an oscillating drum, hand operated means for oscillating said drum, and means for compelling the completion of each stroke prior to starting the stroke in the opposite direction.

7. In combination in a paper folding device, a paper looping device comprising an oscillating drum, hand operated means for oscillating said drum, and means for compelling the completion of each stroke prior to starting the stroke in the opposite direction, said means comprising a reversible pawl or detent adapted to bear against the edge of the drum in either of two positions, and holes in the edge of the drum adapted to engage with said pawl at the end of each stroke for reversing its position.

8. In combination in a paper folding device, a paper looping device comprising an oscillating drum, hand operated means for oscillating said drum, and means for compelling the completion of each stroke prior to starting the stroke in the opposite direction, said means comprising a reversible friction pawl or detent adapted to bear upon the inner edge of the drum in either of two positions, springs for pressing the end of said pawl into frictional contact with said

drum whereby movement of the drum in one or the other direction is prevented, and holes in the edge of the drum adapted to engage with said pawl at the end of each stroke for reversing its position.

9. A paper folding device comprising a frame, an oscillating drum mounted in said frame having a thin folder blade extending lengthwise of the drum and spaced from its surface, a transversely curved clamping blade secured at one edge to said frame and arranged lengthwise of said drum close to its surface, the concave face of said blade being next to the convex periphery of the drum, a movable clamping blade supported at one edge in said frame for movement toward and away from the convex face of said curved clamping blade, the free edge of said movable clamping blade being spaced from the free edge of said curved clamping blade whereby said folder blade can pass between said clamping blades.

10. A paper folding device comprising a frame, an oscillating drum mounted in said frame having a thin folder blade extending lengthwise of the drum and spaced from its surface, a transversely curved clamping blade secured at one edge to said frame and arranged lengthwise of said drum close to its surface, the concave face of said blade being next to the convex periphery of the drum, a movable clamping blade supported at one edge in said frame for movement toward and away from the convex face of said curved clamping blade, said movable clamping blade being flat and adapted to contact tangentially with said curved clamping blade near its secured edge whereby a space is left between the free edges of said clamping blades into which said folder blade can enter.

11. A paper folding device comprising a frame, an oscillating drum mounted in said frame, said drum having a folder blade adapted to coöperate with two clamping blades one of which is fixed and one of which is movable and loosely restrained, said fixed clamping blade being secured to said frame and arranged lengthwise of said drum close to its surface, and said movable clamping blade being guided in said frame for movement toward and away from said fixed clamping blade, said movable clamping blade being freely supported for movement toward and away from said fixed clamping blade, and means arranged at the middle point of said movable clamping blade for pressing it toward said fixed clamping blade.

12. A paper folding device comprising a frame, an oscillating drum mounted in said frame and having a folder blade arranged to enter between a fixed clamping blade which is secured to said frame and arranged lengthwise of said drum close to its surface,

and a movable clamping blade which is freely supported at its inner edge for movement toward and away from said fixed clamping blade, and means arranged at the middle point of the inner edge of said movable clamping blade for pressing it toward said fixed clamping blade.

13. A looping and pasting device comprising a drum, a clamp alongside of the drum for retaining the adjacent ends of a stack of loops in juxtaposition alongside of the drum during the pasting operation, and means for releasing said clamp after the loops have been secured together at their free ends.

14. A looping and pasting device comprising a drum, a clamp alongside of the drum for retaining the adjacent ends of a stack of loops in juxtaposition alongside of the drum during the pasting operation, said stack of loops being foldable around the drum to cause their free ends to be displaced

angularly around the drum, and means for releasing said clamp after the loops have been secured together at their free ends. 25

15. A looping and pasting device comprising a drum, a clamp alongside of the drum for retaining the adjacent ends of a stack of loops in juxtaposition alongside of the drum during the pasting operation, 30 means for releasing said clamp for inserting a cover strip between said stack of loops and said drum, said stack of loops and cover strip being foldable around the drum to cause their free ends to be displaced angularly around the drum, and means for releasing said clamp to free the clamped ends of the loops after they have been secured together and to said cover strip at their 35 free ends. 40

Signed at St. Louis, Missouri, this 2nd day of September, 1915.

WILLIAM H. McBRIDE.
